HERMAN H. RUBIN, OF NEW YORK, N. Y.

POMPON AND METHOD OF MAKING THE SAME

Application filed November 23, 1928. Serial No. 321,409.

The present invention relates to an improvement in pompons and methods of making the same. One object thereof has been to provide a method whereby the cost of making pompons may be materially reduced by eliminating hand operations and in part substituting machine operations. A further object has been to produce a pompon of unusual wear-resisting characteristics without detracting from the appearance of the finished product. A further purpose of the invention has been to provide an improvement whereby a pompon or the like may be securely united to a supporting structure or member for utilitarian as well as ornamental purposes and, when in such relation, to withstand hard wear and usage. Various steps in my improved method and one embodiment of my improved construction are illustrated in the drawing accompanying the present specification and in which

Figure 1 is a plan view representing a group of strands stitched together;

Figure 2, a plan view of a strip of strands;

Figure 3, a perspective view of a portion of a strip of strands;

Figure 4, a perspective view of a plurality of layers of strips assembled for engagement by a retaining member;

Figure 5, a side view of a single strip rolled upon itself and with a retaining member in position;

Figure 6, a section on the line 6—6 of Figure 5 showing a stitch 2 partly removed from one side of a rolled strip of strands; and

Figure 7, a longitudinal sectional view of a pompon used as part of an assist grip, portions of which are broken away to show means for securing the pompon to a supporting member.

Referring to the drawing, a plurality of strands 1 or the like of suitable fibrous or other material are assembled in parallel relation and are bound together by means of stitchings 2 and 3, said stitchings being preferably of the chain type. To form strips, as shown in Figure 2, the strands are cut transversely as between the stitchings

2, 2, thus leaving free ends of the strands exposed along the edges of said strips and adjacent to the lines of stitching 2, the line of stitching 3 thus being positioned substantially midway between two spaced lines of stitching 2. The required number of strands is then bundled or assembled in any desired manner as by rolling a strip, indicated in Figure 5, or by assembling layers of strips, indicated in Figure 4 or otherwise. A retaining member 4 is then passed around the intermediate portion of the assembled strands and tied or otherwise secured thereto in such a manner as to bind said strands firmly in assembled relation. With the strands thus secured, the stitchings 2, 2 are pulled away from the free edges of the strands after which the pompon may then be trimmed to improve or otherwise alter its size, shape or appearance.

Where a pompon is to be attached to a supporting member 5, as for example where it is to be used as part of a grip strap, assist grip or the like, the retaining member is preferably a metallic yoke 6 as of wire arranged to retain the mass of assembled strands against an end of the supporting member 5. The free ends 7 of said yoke interlock with a clamping device 8, such as a staple with its ends bent inwardly and in overlapping relation to form a ring or collar encircling the supporting member 5, which is preferably of some yielding or compressible material as a knitted or twisted fabric, rope, cord or the like. While there are various operative arrangements of interconnection between the ends 7 of yoke 6 and the clamp or ring 8, in a preferred embodiment, said ends 7 pass through said ring and are then bent back upon themselves toward the lower end of the supporting member 5. For greater security, a second ring or collar 9 is clamped around the supporting member 5 and may serve as an abutment or stop adjacent and opposed to the bent back ends 7 of the yoke 6, so that, if the ring 8 should slip or yield under pull, the ring 9 is in position to oppose disengaging movement of the bent back ends. Moreover, when the supporting member comprises a plurality of cords or

rope-like members twisted together, as indicated in Figure 7, ring 9 serves to stiffen the end or butt thereof and prevents the constituent ropes or cords from untwisting. 5. Whatever the form of interconnection for binding the mass of strands 1 to the support 5, the pompon is completed as before by removing the temporary stitchings 2, 2 and, if desired, trimming or otherwise altering 10 its size, shape or appearance. A molding or ferrule 10, of wood or other suitable material, conceals the end of the support 5 and connecting devices associated therewith. As indicated in Figure 7, portions of the inner 15 surface of ferrule 10 bear against the bent back or end portions 7 of yoke 6, thus retaining them securely in operative position. It will be obvious that the connecting means hereinabove described may be utilized 20 to attach grips or ornamental terminal members other than pompons to supports or the like.

The method of manufacture hereinabove set forth produces an extremely durable and 25 artistic appearing product at a greatly reduced labor cost, the pompon construction described, being particularly useful when embodied in a so-called grip strap widely used in automobiles of the closed type. Under 30 severe tests, these pompons connected to the supports as set forth have withstood a disconnecting force or pull of over 500 pounds.

I claim as my invention:

- 35 1. The method of making pompons which includes arranging a plurality of strands in parallel relation, securing said strands together by spaced transversely extending rows of stitching, cutting the strands adjacent to predetermined rows of stitchings, arranging said cut strands in layers, binding said layers together between spaced rows of stitchings, and then removing the stitchings.
- 40 2. The method of making pompons which includes arranging a plurality of strands in parallel relation, securing said strands together by spaced transversely extending rows of stitching, cutting the strands adjacent to predetermined rows to form relatively flat strips of strands having free ends exposed along the edges of said strips, rolling each strip upon itself, securing said strip in rolled relation, and then removing the stitchings.
- 45 3. A pompon comprising a plurality of strands arranged in concentric layers, a row of stitches extending across the strands in each layer, and a retaining member encircling said layers between their lateral edges.
- 50 4. A pompon comprising a plurality of strands in the form of a single strip of strands rolled upon itself to form a bundle

of strands, a row of stitches extending across the strands in said strip, and a retaining member encircling said bundle.

5. The method of making pompons which includes arranging a plurality of strands in parallel relation, temporarily securing spaced portions of said strands together, binding said strands between said spaced portions, and releasing said spaced portions previously secured together. 70

6. The method of making pompons which includes the step of permanently binding together a plurality of strands which are temporarily bound together and then removing the temporary binding. 75

7. The method of making pompons which includes the step of effecting a permanent binding together of a plurality of strands intermediate their ends while said ends are temporarily bound together and then releasing said ends. 80

8. The method of making pompons which includes the steps of securing a plurality of strands together to form a relatively flat strip of strands, rolling said strip upon itself, and binding the strands of said strip while in rolled relation. 85

9. The method of making a pompon which includes the steps of securing a plurality of strands together to form a relatively flat strip of strands, arranging said strip to form layers of strands, and binding said layers of strands to a pompon support. 90

10. A pompon comprising a plurality of superposed layers of strands, a row of strand binding stitches extending across each layer, and a retaining member for holding said layers in superposed relation. 100

11. A pompon comprising a plurality of superposed layers of strands, a row of strand binding stitches extending across each layer, and a retaining member for holding portions of said superposed layers in compressed condition. 105

12. A pompon comprising a plurality of superposed layers of strands, means for retaining the strands of each layer in layer forming arrangement, and a retaining member for holding said layers in assembled relation. 110

13. A pompon comprising a plurality of layers of strands, means for retaining the strands of each layer in layer forming arrangement, and means for holding said layers in assembled relation. 115

14. A pompon comprising a plurality of strands, means for retaining the same in the form of a strip of strands, said strip being rolled upon itself, and means for holding said strip in rolled arrangement. 120

HERMAN H. RUBIN.
